UNITED STATES PATENT OFFICE

WILLIAM O. THEWES, OF NORTH RIDGEVILLE, OHIO

DESIGN FOR A PIPE THREADING DIE HOUSING

Application filed January 5, 1931. Serial No. 38,194. Term of patent 14 years.

To all whom it may concern:

Be it known that I, WILLIAM O. THEWES, a citizen of the United States, residing in North Ridgeville, in the county of Lorain and the State of Ohio, have invented a new, original, and ornamental Design for a Pipe Threading Die Housing, of which the following is a specification, reference being had to the accompanying drawing, forming a part thereof.

Figure 1 is a front elevational view of a pipe threading die housing showing my new design, and

Figure 2 is a side elevation thereof.

I claim:—

The ornamental design for a pipe threading die housing substantially as shown.

WILLIAM O. THEWES.
